KEYHOLE LIGHT

Robert D. Lightfoot, South Bend, Ind.

Application November 17, 1950, Serial No. 13,025

Term of patent 7 years

(Cl. D48—20)

To all whom it may concern:

Be it known that I, Robert D. Lightfoot, a citizen of the United States, a resident of South Bend, in the county of St. Joseph and State of Indiana, whose post office address is 316 S. Carroll Street, city of South Bend, State of Indiana, have invented a new, original, and ornamental Design for a Keyhole Light, of which the following is a specification, reference being made to the accompanying drawing, forming part thereof.

In the drawing:

I claim:

The ornamental design for a keyhole light, substantially as shown and described.

ROBERT D. LIGHTFOOT.
